CARRIER-SIGNAL DETECTOR

Nelson P. Case, Great Neck, N. Y., assignor to
Hazeltine Corporation, a corporation of Delaware

Application February 25, 1941, Serial No. 380,448

12 Claims. (Cl. 250—20)

The present invention relates to carrier-signal detectors and, more particularly, to such detectors of the type adapted effectively to increase the amplitude of the carrier-frequency component of a modulated-carrier signal applied thereto with respect to its modulation sidebands.

Present-day radio carrier-signal systems are subject to distortion of the received carrier signal due to the phenomenon of fading. Fading, in general, occurs when the carrier signal is transmitted to the receiver in large part by reflection from the Kennelly-Heaviside ionized layer surrounding the earth. Generally, the carrier-frequency component and the sideband components simultaneously travel over a number of individual paths including one or more reflections from the ionized layer. One of the most severe cases of distortion occurs when the carrier-frequency component in travelling over its path or paths to the receiver decreases in intensity materially with respect to certain portions of the modulation sidebands, thereby effectively to produce over-modulation of the carrier wave. Such relative changes of intensity of the carrier signal and certain portions of its modulation sidebands are commonly referred to as selective fading.

It has been proposed in accordance with one prior art arrangement that the effect of selective fading be reduced by the method of separating at the receiver the carrier-frequency component from its modulation sidebands and thereafter combining with the modulation sidebands, before detection, a carrier wave of relatively high and constant intensity derived either from a synchronized local oscillator or by amplification of the separated carrier-frequency component to a predetermined constant level. An arrangement of this nature has the disadvantage that it is difficult to maintain the proper phase relation between the constant intensity carrier wave and the sidebands with which it is combined, a condition that is essential to distortionless reproduction of the modulation components of the received carrier signal. The arrangement has the additional disadvantage of undue complexity of apparatus and circuit arrangement.

It has been proposed in accordance with another prior art arrangement that the carrier-frequency component be effectively increased in

amplitude with respect to its modulation sidebands in each of two carrier-signal channels of a receiver, the outputs of the two channels being rectified and combined to derive the modulation components of the carrier signal. Such emphasis of the carrier-frequency component is effected by neutralized piezo-electric crystals effectively individually in series in the carrier-signal channels. This prior art arrangement has a disadvantage, aside from the complexity of the circuit arrangement necessary to effect the desired result, that the signal channels have a number of tuned circuits individual to each which are difficult to maintain in precise adjustment over any appreciable period of time and which consequently tend to introduce distortion into the reproduced signal by virtue of such misadjustment. Furthermore, the use of a piezo-electric crystal in this manner in a superheterodyne 10 type of carrier-signal receiver necessitates some form of automatic frequency control system requiring a frequency detector in addition to an amplitude-modulation detector.

It is an object of the invention, therefore, to provide an improved carrier-signal detector wherein the amplitude of the carrier-frequency component of the carrier wave is greatly increased with respect to its sideband components to reduce the effect of selective fading in producing distortion of the reproduced signal.

It is a further object of the invention to provide, in a carrier-signal receiver of the superheterodyne type, a combined amplitude and frequency carrier-signal detector having input circuits of extraordinarily high ratio of inductive reactance to resistance of the order of ten thousand to one, whereby the amplitude carrier-frequency component is effectively increased with respect to its modulation sidebands and from 35 which an automatic frequency control potential is derived for maintaining the intermediate-frequency carrier signal within a few cycles of the mean frequency to which the intermediate-frequency signal channel of the receiver is tuned.

It is an additional object of the invention to provide a combined carrier-signal detector and automatic amplification control system in which the carrier-frequency component of a received carrier signal is effectively increased with respect 40 to its modulation sidebands and the magnitude

of the automatic amplification control bias varies in accordance with the intensity of both the carrier-frequency component and the modulation sidebands thereof, thereby greatly to reduce the tendency of selective fading to cause improper reproduction of the reproduced signal.

In accordance with the invention, a modulated carrier-signal detector comprises a frequency-selective network including a transformer having primary and secondary windings and means coupling the windings to provide two network sections, and a single piezo-electric crystal device coupled effectively in shunt to at least portions of both of the sections to cause each of the network sections to have predetermined frequency-response characteristics of the same type with a maximum response substantially at the nominal carrier frequency of a carrier signal to be applied to the network and a minimum response at an individual one of two frequencies spaced substantially equally on opposite sides of the carrier frequency. The detector includes a pair of rectifier devices individually coupled to the network sections, each of the devices having an individual load impedance across which there is developed a unidirectional modulation voltage, and an output circuit for utilizing at least one of the developed unidirectional voltages.

In accordance with a preferred form of the invention, a carrier-signal detector of the type described comprises a frequency-selective network including coupled primary and secondary windings and means for deriving voltages equal to the sum and difference of predetermined portions of the voltages developed in said windings by a carrier signal applied thereto. The detector includes piezo-electric crystal means coupled in shunt to the secondary winding for so modifying the frequency response of the network that each of the developed voltages has maximum amplitude substantially at the nominal carrier frequency of the carrier signal and a minimum amplitude at an individual one of two frequencies spaced substantially equally on opposite sides of the carrier frequency. In this preferred form of the invention, the secondary winding preferably includes two sections and that portion of the primary winding voltage which is combined with the secondary winding voltage to derive the aforesaid sum and difference voltages is of the order of one-tenth of the maximum voltage developed in either section of the secondary winding. A pair of similar inductors are preferably serially connected in circuit with the piezo-electric means and on opposite sides thereof for modifying the frequency-response characteristic of the network sections to eliminate the effect thereon of one of the resonant responses of the piezo-electric means. The detector includes means for deriving a unidirectional control potential from the voltage developed across the primary winding by the applied carrier signal, the magnitude of this control potential varying with the intensity both of the applied carrier signal and its modulation sidebands.

For a better understanding of the invention, together with other and further objects thereof, reference is had to the following description taken in connection with the accompanying drawing, and its scope will be pointed out in the appended claims.

Referring now to the drawing, Fig. 1 is a circuit diagram, partly schematic, of a complete carrier-signal receiver of the superheterodyne type embodying the invention; and Figs. 2-8, inclu-

sive, are graphs representing frequency-response characteristics of one or more circuit components of the Fig. 1 arrangement and are used as an aid in explaining the operation of the invention.

5 Referring now more particularly to Fig. 1 of the drawing, there is represented schematically a complete superheterodyne carrier-signal receiver of a conventional design embodying the present invention in a preferred form. In general, the 10 receiver includes a radio-frequency amplifier 10 having its input circuit connected to an antenna system 11, 12 and having its output circuit connected to an oscillator-modulator 13. Connected in cascade with the oscillator-modulator 13, in 15 the order named, are an intermediate-frequency amplifier 14 of one or more stages, an intermediate-frequency amplifier 15, a combined carrier-signal detector, automatic amplification control or A. V. C. supply, and automatic frequency control supply 16, more fully described hereinafter, an audio-frequency amplifier 17 of one or more stages, and a sound reproducer 18.

The output of the automatic frequency control supply of unit 16 is coupled to the input of a frequency shifter 19, the output of which is coupled, in turn, to the oscillator of unit 13.

An automatic amplification control or A. V. C. circuit is connected between the output of the A. V. C. supply of unit 16 and the input circuits 30 of one or more of the tubes of the radio-frequency amplifier 10, the oscillator-modulator 13, and the intermediate-frequency amplifier 14 in conventional manner.

It will be understood that the various units just 35 described may, with the exception of unit 16, be of a conventional construction and operation, the details of which are well known in the art, rendering detailed description thereof unnecessary. Considering, briefly, the operation of the 40 receiver as a whole and neglecting for the moment the operation of unit 16 presently to be described, a desired carrier signal is selected and amplified by the radio-frequency amplifier 10, converted to an intermediate-frequency carrier 45 signal in the oscillator-modulator 13, amplified in intermediate-frequency amplifier 14, and detected by the carrier-signal detector of unit 16, thereby to derive the audio-frequency modulation components. The audio-frequency components are, in turn, amplified in the audio-frequency 50 amplifier 17 and are reproduced by the sound reproducer 18 in a conventional manner.

The automatic frequency control bias derived 55 from the automatic frequency control supply of unit 16 is effective to control the frequency shifter 19 and thereby the operating frequency of the oscillator of unit 13 to maintain the frequency of the intermediate-frequency carrier signal within a few cycles of the nominal frequency 60 of the pass band of the intermediate-frequency amplifier 14.

The automatic amplification control or A. V. C. bias derived from the A. V. C. supply of unit 16 is effective to control the amplification of one or 65 more of the units 10, 13, and 14 to maintain the signal input to the detector of unit 16 within a relatively narrow range for a wide range of received signal intensities.

Referring now more particularly to the portion 70 of the system embodying the present invention, there is coupled to the output of the intermediate-frequency amplifier 15 a combined carrier-signal detector, automatic amplification control or A. V. C. supply, and automatic frequency control or A. F. C. supply 16. The carrier-signal

detector of unit 16 comprises a frequency-selective network 20 including two sections and a single piezo-electric crystal device 21 coupled effectively in shunt to at least portions of both of the sections to cause each of the network sections to have predetermined frequency-response characteristics of the same type. The frequency-selective network 20 includes a transformer 9 having a primary winding 22 and a center-tapped secondary winding 23, each half of the secondary winding comprising one section of the network 20. Condensers 24, 25 are connected across the windings 22, 23, respectively, to tune them to the frequency of the intermediate-frequency carrier signal.

In order to derive two voltages equal to the sum and difference of predetermined portions of the voltages developed in the transformer windings 22, 23 by an intermediate-frequency carrier signal applied thereto, there is provided means coupling the windings to provide two network sections comprising a coupling condenser 26 connected between the high alternating-potential terminal of the primary winding 22 and the center tap of the secondary winding 23. The condenser 26 is effective to apply a portion of the voltage developed in the primary winding 22 by the intermediate-frequency carrier signal to each secondary circuit including a half of the secondary winding 23. The portion of the primary winding voltage which is applied by the condenser 26 to the secondary circuit is determined by the value of the condenser 26 which preferably is sufficiently small that the portion of the primary voltage applied through the condenser is of the order of one-tenth the maximum voltage developed in either half of the secondary winding. While the circuit arrangement of the frequency-selective network thus far described is of the conventional split-phase type, the preferred value of the condenser 26 is materially smaller than that conventionally used.

A pair of similar inductors 27, 28 are serially connected in circuit with the piezo-electric crystal 21 and on opposite sides thereof. A pair of rectifier devices such as diodes 29, 30 are coupled to individual halves of the secondary winding 23, and thereby to individual sections of the network 20, by individual load impedances 31, 32, respectively. A common direct current path, comprising a radio-frequency choke 33, is also provided. Unidirectional modulation voltages are developed across each of the load impedances 31, 32 and a first pair of output-circuit terminals 34, 35, which are included in an output circuit for utilizing at least one of the unidirectional voltages, are coupled to the load impedance 32 and to the input circuit of the audio-frequency amplifier 17 for applying to the latter the developed modulation voltage. A second output circuit comprising the output terminals 35, 36 is coupled across both of the load impedances 31, 32 in series and to the input circuit of the frequency shifter 19, thereby to derive and to apply to the frequency shifter a unidirectional automatic frequency control bias.

The automatic amplification control supply of unit 16 comprises a rectifier device 37 and a load impedance 38 therefor coupled across the primary winding 22 through a coupling condenser 39. The output of the automatic amplification control supply is coupled through a filter network comprising series-resistance arms 40, 41 and a shunt-capacitance arm 42 to the input

circuits of one or more of the tubes of units 10, 13, and 14, as previously explained.

Before considering the operation of the circuit just described as a whole, it may be noted that the piezo-electric crystal 21 has a frequency-reactance characteristic represented by the curves of Fig. 2. The crystal is series-resonant at the frequency f_1 and parallel-resonant at the frequency f_2 . If it be assumed at this point that the coupling condenser 26 be omitted and the inductors 27, 28 be short-circuited from the circuit of the detector of unit 16 and the rectifier device 30 be replaced by a bilaterally conductive path, the voltage developed across the load impedances 31, 32 in series, with variations of frequency of the intermediate-frequency carrier signal, would be as represented in Fig. 3. This voltage would have minimum amplitude at the series-resonant frequency f_1 and maximum amplitude at the parallel-resonant frequency f_2 of the crystal. The parallel-resonant frequency of the crystal 21 is chosen equal to the nominal frequency of the pass band of intermediate-frequency amplifier 14.

Now, if the inductors 27 and 28 be connected in series with the crystal 21 across the transformer secondary winding 23, and without any other changes of the detector circuit from that assumed above, the inductors 27 and 28 modify the frequency reactance characteristic of the crystal. It has been found that, by properly proportioning the values of inductors 27, 28 with respect to the reactive constants of the selective network, particularly with respect to the capacitance in shunt to the crystal 21, which capacitance is comprised primarily by the capacitance of the crystal holder, the unidirectional potential developed across the load impedances 31 and 32 in series can be made to vary in amplitude with the frequency of the intermediate-frequency carrier signal as represented by the curve of Fig. 4 and to have maximum amplitude substantially at the parallel-resonant frequency f_2 of the crystal. Thus, the crystal and the inductors 27, 28 together simulate a parallel-resonant highly-selective circuit having a ratio of inductive reactance to resistance of the order of ten thousand to one.

In considering the operation of the detector of unit 16 in the complete form shown in the drawing, reference is made to Fig. 5 which is a vector diagram representing the magnitude and phase relationships of the voltages developed in the frequency-selective network 20 by an intermediate-frequency carrier signal applied thereto. When the intermediate-frequency carrier signal has a frequency equal to the mean frequency of the network 20, there are developed across the two halves of the secondary winding 23 individual voltages, represented by the vectors a and b , which are displaced in phase 180 degrees with respect to each other and 90 degrees with respect to the voltage developed across the primary winding 22, the vector c representing that portion of the latter voltage which is applied through the condenser 26 to the secondary winding 23. The voltages applied to the rectifier devices 29 and 30 are the vectorial sums of the primary voltage vector c and individual ones of the vector voltages a , b and are represented in Fig. 5 by the vectors d and e , respectively. As the frequency of the intermediate-frequency carrier signal deviates from the mean frequency of the network 20, the voltages induced in each network section change in magnitude while

maintaining their relative 180-degree phase displacement but vary in phase with respect to the voltage c developed across the primary winding 22, the magnitude of the latter voltage remaining substantially constant over a relatively wide range of frequency deviations of the intermediate-frequency carrier signal by virtue of the relatively broadly-selective characteristic of the tuned circuit comprising primary winding 22 and condenser 24. The vectors f and g represent, for example, the magnitude and phase of the secondary voltages in the network 20 at a particular value of deviation of the intermediate-frequency carrier signal, the resultants of these voltages and the primary voltage c being represented by the vectors a' and e' . The circles h and i represent the loci of the ends of the vectors a and b , respectively, with deviations of the intermediate-frequency carrier signal over a wide range of frequency deviation on each side of and including the mean frequency of the network 20. It has previously been stated that the condenser 26 is sufficiently small that the portion of the primary winding voltage which is applied to each half of the secondary winding 23 is of the order of one-tenth the maximum voltage developed in either half of the secondary winding. It may be noted at this point that the vector c of Fig. 5 has not been drawn to scale with respect to the vectors a and b since to do so would more confuse than aid in arriving at an understanding of the operation of the invention. It will be evident, therefore, that the resultants of the primary and secondary voltages have minimum amplitudes at the points k and m on the respective circles h and i , these points corresponding to equal wide deviations of the carrier signal at opposite sides of the mean frequency of network 20, and that the resultant voltages have larger than minimum amplitudes for frequency deviations in excess of these values. Thus, the sum and difference voltages developed by the two sections of the frequency-selective network 20 have frequency-amplitude characteristics as represented by the broken-line curve A and solid-line curve B of Fig. 6, which are of the same type but oppositely directed with respect to the nominal intermediate carrier frequency. The maximum amplitudes of curves A and B occur substantially at the nominal carrier frequency of the intermediate-frequency carrier signal. The minimum amplitude of curve A occurs at a frequency f_7 , which corresponds to the frequency represented by the point k on the circle h , of Fig. 5 and the minimum amplitude of curve B occurs at a frequency f_8 , which corresponds to the point m on the circuit i .

The vector diagram of Fig. 5 in several respects is not representative of the conventional prior art split-phase frequency-responsive network. In the first place, in the conventional prior art networks of this nature the primary voltage vector, corresponding to vector c of Fig. 5, is at least as large as, or larger than, the secondary voltage vectors, corresponding to vectors a and b of Fig. 5. Secondly, the conventional prior art networks include primary and secondary network sections having substantially equal ratios of inductive reactance to resistance, generally of the order of two hundred to one at most, with the result that the changes of the primary and secondary voltage vectors with the frequency of the intermediate-frequency carrier signal are of the same order of

magnitude whereas in applicant's arrangement, as pointed out above, the primary voltage vector c , Fig. 5, remains substantially constant in magnitude over the range of frequencies of the intermediate-frequency carrier signal within which the major part of the phase and amplitude changes of the secondary voltage vectors occur.

Thus, the frequency-response characteristic of the network 20 is so modified by the crystal 21 and inductors 27, 28 that each of the sum and difference voltages developed by the two network sections has a maximum amplitude substantially at the nominal carrier frequency of the intermediate-frequency carrier signal and a minimum amplitude at an individual one of two frequencies spaced substantially equally on opposite sides of the nominal carrier frequency of the intermediate-frequency carrier signal. The unidirectional voltages developed across the load impedances 31 and 32 have amplitude-frequency characteristics similar to curves A and B of Fig. 6. It is evident from these curves that the unidirectional modulation voltage developed across either of the load impedances 31 or 32 is similar to what would be procured if the intensity of the intermediate-frequency carrier signal were greatly increased with respect to its modulation sidebands. By virtue of this fact, the carrier signal, in practice, seldom becomes over-modulated even though the intensity of the received signal carrier materially decreases with respect to the intensity of its sidebands due to selective fading. Consequently, the effect of selective fading in causing distortion of the reproduced signal is greatly reduced. Therefore, the pair of inductors 27, 28 which are serially connected in circuit with the piezo-electric means 21, and on opposite sides thereof, modify the frequency-response characteristic of the network sections to eliminate the effect thereon of one of the resonant responses of the piezo-electric means. The inductors are so proportioned with respect to the capacitance in shunt to the piezo-electric means 21 that the network sections have predetermined frequency-response characteristics of the same type with a peak response substantially at the nominal carrier frequency of the carrier signal and a minimum response at an individual one of two frequencies spaced substantially equally on opposite sides of the carrier frequency.

It will thus be seen that the piezo-electric crystal device coupled effectively in shunt to the sections of the network 20 maintains a high degree of response of the network sections to the carrier-frequency component while attenuating the response of the sections to the frequencies comprising the sidebands of the carrier signal applied to the network. Expressed somewhat differently, the piezo-electric crystal means, which is coupled in shunt to the secondary winding 23, so modifies the frequency-response of the network that each of the voltages has a maximum amplitude substantially at the nominal carrier frequency of the carrier signal and a minimum amplitude at an individual one of two frequencies spaced substantially equally on opposite sides of the carrier frequency. The piezo-electric crystal 21, therefore, comprises means having a plurality of resonant responses, which responses include a parallel-resonant response substantially at the nominal carrier frequency of the carrier signal to be applied to the network, for modifying the frequency response of the network 20 as described.

The separation of the series-resonant and parallel-resonant frequencies f_1 and f_2 of Figs. 2 and 3 is not represented to scale for purposes of simplifying the drawing, the separation of these frequencies in practice being of the order of 200 cycles when the crystal 21 has a parallel-resonant frequency of 456 kilocycles, which corresponds closely to the usual intermediate frequency employed in present-day broadcast carrier-signal receivers. Likewise, the frequency separation of the points of minimum amplitude of curves A and B of Fig. 6 is not represented to scale, but is in practice also very small. It is, therefore, evident that the crystal 21 comprises means for greatly narrowing the frequency-response characteristic of the two sections of the network 20. The inductors 21, 28 comprise means coupled in circuit with the piezo-electric crystal 21 for modifying the frequency-response characteristic of the two sections of the network 20 to eliminate the effect thereon of one of the resonant responses of the piezo-electric crystal.

The output circuit comprising the output terminal 36 of the automatic frequency control system is coupled to both of the load impedances 31, 32 in series, differentially to combine the unidirectional modulation voltages developed thereacross to derive and utilize a unidirectional control potential, the magnitude and polarity of which vary, respectively, with the degree and direction of departure of the intermediate carrier frequency from the mean resonant frequency of the network sections. The amplitude-frequency characteristic of this derived unidirectional control potential is represented by the curve of Fig. 7. The control potential is applied to the input of the frequency shifter 19, thereby to control the frequency of oscillations generated by the oscillator of unit 13 to maintain the carrier frequency of the intermediate-frequency carrier signal substantially at the mean frequency of the pass band of the intermediate-frequency amplifier 14.

The frequency-response characteristic of the tuned primary circuit comprising the primary winding 22 and the condenser 24 is represented by the curve of Fig. 8. Because of the coupling of the tuned secondary circuit comprising the secondary winding 23, the condenser 25, and the piezo-electric crystal 21 and inductors 21, 28 to the tuned primary circuit, the latter has greatly decreased response at the nominal carrier frequency of the intermediate-frequency carrier signal, but has nearly uniformly high response at the frequencies comprising the modulation sidebands of the carrier signal. On the other hand, the carrier component of the carrier signal has an appreciably larger amplitude than any of the sideband component frequencies. Consequently, the automatic amplification control system comprising the rectifier device 37 is responsive to, and the unidirection control potential derived thereby varies in accordance with, the intensity of both the carrier-frequency component of the intermediate-frequency carrier signal and the sideband components thereof. The control bias, therefore, does not vary unduly in magnitude upon the occurrence of selective fading of the received carrier signal. The unidirectional control bias derived by the automatic amplification control system of unit 16 is utilized to control a characteristic of the signal translating channel of units 10, 13, and 14, that is, to control the amplification characteristic of

these units to maintain the signal input to the detector of unit 16 within a relatively narrow range for a wide range of received signal intensities.

As illustrative of a specific embodiment of the invention, the following circuit constants are given for an embodiment of the invention of the type shown in Fig. 1:

10	Rectifier devices 29 and 30	Type 6H6 vacuum tube
	Rectifier device 37	Type 6H6 vacuum tube
	Load impedances 31 and 32:	
	Resistor	1 megohm
	Condenser	100 micromicrofarads
15	Resistors 38, 40 and 41	1 megohm
	Condensers 24 and 25	50-150 micromicrofarads
	Condenser 26	Approximately 2 micromicrofarads
20	Condenser 39	100 micromicrofarads
	Condenser 42	0.01 microfarad
	Primary winding 22	1.11 millihenries
25	Secondary winding 23	1.11 millihenries
	Mutual inductance 22, 23	0.03 millihenry
	Radio-frequency choke 33	4.5 millihenries
	Inductors 27 and 28, each	4.1 millihenries
30	Piezo-electric crystal 21 anti-resonant frequency	456 kilocycles

The invention is adapted for use in a single-sideband amplitude-modulated carrier receiver, the only change in the receiver from that described above being that the band-pass selectors of the intermediate-frequency amplifier 14 are so tuned that the nominal intermediate carrier frequency normally lies near one edge of the pass band of the band-pass selectors of unit 14. In this event, the frequency shifter 19 maintains the frequency of the intermediate-frequency carrier signal at a frequency corresponding substantially to that of one edge of the pass-band characteristic of the band-pass selectors of unit 14. The operation of a carrier-signal receiver of this type is the same as that described above except that only the carrier-frequency component and one sideband component of the received carrier signal are applied to unit 16. When the unit 14 of the carrier-signal translating channel is of the type hereinbefore described as adapted to translate the carrier frequency component and one sideband component of the carrier wave which is applied thereto, it will be evident that the single piezo-electric crystal device 21 is coupled effectively in shunt to at least portions of both of the network sections for effecting in the network sections maximum response at the nominal carrier frequency of the carrier wave and an attenuated response at the frequencies comprising the translated sideband component.

While the invention has been described as embodied in an amplitude-modulated carrier-signal receiver, it will be evident that it is equally well suited for use in a frequency-modulated carrier-signal receiver. In this event, the output terminal 34 of unit 16 is connected to the cathode of the rectifier device 29 to form a frequency-modulation detector of conventional form. The frequency shifter 19 maintains the nominal frequency of the frequency-modulated intermediate-frequency carrier signal at the mean frequency of intermediate-frequency amplifier 14. The intermediate-frequency amplifier 14 may include,

if desired, an amplitude-limiting system of conventional form.

While there has been described what is at present considered to be the preferred embodiment of this invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. A modulated carrier-signal detector comprising, a frequency-selective network including a transformer having primary and secondary windings and means coupling said windings to provide two network sections, a single piezo-electric crystal device coupled effectively in shunt to at least portions of both of said sections to cause each of said network sections to have predetermined frequency-response characteristics of the same type with a maximum response substantially at the nominal carrier frequency of a carrier signal to be applied to said network and a minimum response at an individual one of two frequencies spaced substantially equally on opposite sides of said carrier frequency, a pair of rectifier devices individually coupled to said sections, each of said devices having an individual load impedance across which there is developed a unidirectional modulation voltage, and an output circuit for utilizing at least one of said unidirectional voltages.

2. A modulated carrier-signal detector comprising, a frequency-selective network including coupled primary and secondary windings and means for deriving voltages equal to the sum and difference of predetermined portions of the voltages developed in said windings by a carrier signal applied thereto, piezo-electric crystal means coupled in shunt to said secondary winding for so modifying the frequency response of said network that each of said voltages has a maximum amplitude substantially at the nominal carrier frequency of said carrier signal and a minimum amplitude at an individual one of two frequencies spaced substantially equally on opposite sides of said carrier frequency, a pair of rectifier devices individually coupled to the secondary winding of said transformer, each of said devices having an individual load impedance across which there is developed a unidirectional modulation voltage, and an output circuit for utilizing at least one of said unidirectional voltages.

3. A modulated carrier-signal detector comprising, a frequency-selective network including two sections and a single piezo-electric crystal device coupled effectively in shunt to at least portions of both of said sections, said piezo-electric means having a plurality of resonant responses including a parallel resonant response substantially at the nominal carrier frequency of a carrier signal to be applied to said network, means coupled in circuit with said piezo-electric means for modifying the frequency-response characteristic of said network sections to eliminate the effect thereon of one of the resonant responses of said piezo-electric means, whereby each of said network sections has a predetermined frequency-response characteristic of the same type with a maximum response substantially at the nominal carrier frequency of said carrier signal and a minimum response at an individual one of two frequencies spaced substantially equally on opposite sides of said carrier frequency, a pair of

rectifier devices individually coupled to said sections, each of said devices having an individual load impedance across which there is developed a unidirectional modulation voltage, and an output circuit for utilizing at least one of said unidirectional voltages.

4. A modulated carrier-signal detector comprising, a frequency-selective network including two sections and piezo-electric means coupled in shunt to at least portions thereof, said piezo-electric means having parallel resonance substantially at the nominal carrier frequency of a carrier signal to be applied to said network, a pair of inductors serially connected in circuit with said piezo-electric means and on opposite sides thereof for modifying the frequency-response characteristic of said network sections to eliminate the effect thereon of one of the resonant responses of said piezo-electric means, whereby each of said sections has a predetermined frequency-response characteristic of the same type with a maximum response substantially at the nominal carrier frequency of said carrier signal and a minimum response at an individual one of two frequencies spaced substantially equally on opposite sides of said carrier frequency, a pair of rectifier devices individually coupled to said sections, each of said devices having an individual load impedance across which there is developed a unidirectional modulation voltage, and an output circuit for utilizing at least one of said unidirectional voltages.

5. A modulated carrier-signal detector comprising, a frequency-selective network including two sections and piezo-electric means coupled in shunt to at least portions thereof, said piezo-electric means having parallel resonance substantially at the nominal carrier frequency of a carrier signal to be applied to said network, a pair of similar inductors serially connected in circuit with said piezo-electric means and on opposite sides thereof, said inductors being so proportioned with respect to the capacitance in shunt to said piezo-electric means that said network sections have predetermined frequency-response characteristics of the same type with a peak response substantially at the nominal carrier frequency of said carrier signal and a minimum response at an individual one of two frequencies spaced substantially equally on opposite sides of said carrier frequency, a pair of rectifier devices individually coupled to said sections, each of said devices having an individual load impedance across which there is developed a unidirectional modulation voltage, and an output circuit for utilizing at least one of said unidirectional voltages.

6. A modulated carrier-signal detector comprising, a frequency-selective network including a primary winding and a two-section secondary winding and means for combining a relatively small portion of the voltage developed in said primary winding by a carrier signal applied thereto with the voltage developed in each section of said secondary winding, thereby to derive two voltages equal to the sum and difference of said combined voltages, piezo-electric crystal means coupled in shunt to said secondary winding for so modifying the frequency response of said network that each of said voltages has maximum amplitude substantially at the nominal carrier frequency of said carrier signal and minimum amplitude at an individual one of two frequencies spaced substantially equally on opposite sides of said carrier frequency, a pair of recti-

fier devices individually coupled to the two sections of said secondary winding, each of said devices having an individual load impedance across which there is developed a unidirectional modulation voltage, and an output circuit for utilizing at least one of said unidirectional voltages.

7. A modulated carrier-signal detector comprising, a frequency-selective network including a primary winding and a two-section secondary winding and means for combining a relatively small portion of the voltage developed in said primary winding by a carrier signal applied thereto with the voltage developed in each section of said secondary winding, thereby to derive two voltages equal to the sum and difference of said combined voltages, the said portion of said primary voltage having a magnitude of the order of one-tenth that of the maximum voltage developed in either section of said secondary winding, piezo-electric crystal means coupled in shunt to said secondary winding for so modifying the frequency response of said network that each of said voltages has maximum amplitude substantially at the nominal carrier frequency of said carrier signal and minimum amplitude at an individual one of two frequencies spaced substantially equally on opposite sides of said carrier frequency, a pair of rectifier devices individually coupled to the two sections of said secondary winding, each of said devices having an individual load impedance across which there is developed a unidirectional modulation voltage, and an output circuit for utilizing at least one of said unidirectional voltages.

8. A modulated carrier-signal detector comprising, a frequency-selective network including a transformer having primary and secondary windings and means coupling said windings to provide two network sections, a single piezo-electric crystal device coupled effectively in shunt to at least portions of both of said sections, each of said network sections having predetermined frequency-response characteristics of the same type with a maximum response substantially at the nominal carrier frequency of a carrier signal to be applied to said network and a minimum response at an individual one of two frequencies spaced substantially equally on opposite sides of said carrier frequency, a pair of rectifier devices individually coupled to said sections, each of said devices having an individual load impedance across which there is developed a unidirectional modulation voltage, an output circuit coupled to one of said load impedances for utilizing one of said unidirectional voltages, and a second output circuit coupled to both of said load impedances for deriving and for utilizing a unidirectional control potential, the magnitude and polarity of which vary respectively with the degree and direction of departure of the carrier frequency from the mean resonant frequency of said network sections.

9. A modulated carrier-signal detector comprising, a frequency-selective network including primary and secondary windings and means for deriving voltages equal to the sum and difference of predetermined portions of the voltages developed in said windings by a carrier signal applied thereto, piezo-electric crystal means coupled in shunt to said secondary winding for so modifying the frequency response of said network that each of said voltages has maximum amplitude substantially at the nominal carrier frequency of said carrier signal and minimum amplitude at an individual one of two frequencies

spaced substantially equally on opposite sides of said carrier frequency, a pair of rectifier devices individually coupled to the secondary winding of said transformer, each of said devices having an individual load impedance across which there is developed a unidirectional modulation voltage, an output circuit for utilizing at least one of said unidirectional voltages, means for deriving a unidirectional control potential from the voltage developed across said primary winding by said carrier signal, the magnitude of said control potential varying with the intensity of both the carrier-frequency component of said applied carrier signal and its modulation sidebands, and a second output circuit for utilizing said unidirectional control potential.

10. In a modulated carrier-signal receiver of the superheterodyne type including a local oscillator and frequency control system therefor, a carrier-signal translating channel, and an audio-frequency amplifier, a carrier-signal detector comprising, a frequency-selective network including primary and secondary windings and means for deriving voltages equal to the sum and difference of predetermined portions of the voltages developed in said windings by a carrier signal applied thereto, piezo-electric crystal means coupled in shunt to said secondary windings for so modifying the frequency response of said network that each of said voltages has maximum amplitude substantially at the nominal carrier frequency of said carrier signal and minimum amplitude at an individual one of two frequencies spaced substantially equally on opposite sides of said carrier frequency, a pair of rectifier devices individually coupled to said secondary winding, each of said devices having an individual load impedance across which there is developed a unidirectional modulation voltage, means for deriving a unidirectional control potential from the carrier-signal voltage developed across said primary winding and for utilizing said control potential for controlling a characteristic of said signal-translating channel, a first output circuit coupled to one of said load impedances for applying the unidirectional modulation voltage developed thereacross to said audio-frequency amplifier, and a second output circuit coupled to both of said load impedances in series for applying both of said unidirectional modulation voltages to said frequency control system to control the frequency of said local oscillator.

11. A modulated carrier-signal detector comprising, a frequency-selective network including a transformer having primary and secondary windings and means coupling said windings to provide two network sections, a single piezo-electric crystal device coupled effectively in shunt to at least portions of both of said sections for maintaining the response of said network sections to the carrier frequency and for attenuating the response of said sections to frequencies comprising the sidebands of a carrier signal applied to said network, a pair of rectifier devices individually coupled to said sections, each of said devices having an individual load impedance across which there is developed a unidirectional modulation voltage, and an output circuit for utilizing at least one of said unidirectional voltages.

12. In a modulated carrier-signal receiver including a carrier-signal translating channel adapted to translate the carrier-frequency component and one sideband component of a carrier wave applied thereto, a carrier-signal detector comprising, a frequency-selective network cou-

pled to said channel and including a transformer having primary and secondary windings and means coupling said windings to provide two network sections, a single piezo-electric crystal device coupled effectively in shunt to at least portions of both of said network sections for effecting in said network sections maximum response at the nominal carrier frequency of said carrier wave and an attenuated response at the fre-

quencies comprising said translated sideband component, a pair of rectifier devices individually coupled to said sections, each of said devices having an individual load impedance across which there is developed a unidirectional modulation voltage, and an output circuit for utilizing at least one of said unidirectional modulation voltages.
